Primary Examiner—Clare E Heflin(74) *Attorney, Agent, or Firm*—Bracewell & Giuliani LLP(57) **CLAIM**

The ornamental design for a light fixture, as shown and described.

DESCRIPTION

FIG. 1 is a perspective view of the light fixture showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is an additional side elevational view thereof.

The broken lines depict environmental subject matter only and form no part of the claimed design.
